(57) **CLAIM**

The ornamental design for a tool hook as shown and described.

DESCRIPTION

FIG. 1 is a top front left perspective view of the tool hook of the present invention;

FIG. 2 is a bottom front right perspective view thereof;

FIG. 3 is a front view thereof;

FIG. 4 is a left side view thereof;

FIG. 5 is a right side view thereof;

FIG. 6 is a top view thereof;

FIG. 7 is a bottom view thereof;

FIG. 8 is a bottom front left perspective view thereof; and, FIG. 9 is a top front right perspective view thereof.

The portions of the figures illustrated in broken lines form no part of the claimed design for the tool hook.

1 Claim, 9 Drawing Sheets
